UNITED STATES PATENT OFFICE.

MATHIAS BLEICHNER, OF OGILVIE, MINNESOTA.

MAIL-BOX.

1,177,008.

Specification of Letters Patent. Patented Mar. 28, 1916.

Application filed February 17, 1915. Serial No. 8,801.

To all whom it may concern:

Be it known that I, MATHIAS BLEICHNER, a citizen of the United States, residing at Ogilvie, in the county of Kanabec and State of Minnesota, have invented certain new and useful Improvements in Mail-Boxes, of which the following is a specification, reference being had to the accompanying drawings.

- 10 This invention relates to new and useful improvements in mail boxes and more particularly to rural mail boxes, the main object of the present invention being the provision of a mail box of this character having 15 manually operated means whereby the cover can be quickly and readily opened to gain access to the interior of the box and, at the same time, a portion of the box will be opened simultaneously with the cover.
- 20 Another object of the present invention is the provision of a device of the above character which will possess advantages in points of efficiency and durability, is inexpensive to manufacture and, at the same 25 time, is simple in construction and operation.

With the above and other objects in view, the invention consists in the novel features of construction, combination and arrangement of parts as will be hereinafter referred to and more particularly pointed out in the specification and claims.

In the accompanying drawings forming a part of this application, Figure 1 is a detail perspective view of a mail box constructed in accordance with my invention. Fig. 2 is a transverse sectional view of the same. Fig. 3 is a longitudinal sectional view taken on the line 3-3, Fig. 2, illustrating the cover in its open position. Fig. 4 is a detail bottom perspective view of the supporting bottom; and Fig. 5 is a detail perspective view of the upper edge of the rigid portion of the forward wall of the box, illustrating the yieldable flange formed thereon.

In carrying out my invention, I provide a support or standard 1, which is provided with a central longitudinal bore 2, in which 50 is arranged a metal casing 3 having at its upper edge an annular rib 4 adapted to bear upon the upper end of the base or support and movably arranged within the casing 3, is a hollow standard 5 which is securely 55 held in an adjusted position within the casing 3 by means of a set screw 6 which ex-

tends through the rib 4 and engages the outer surface of the standard 5. Secured to the standard 5, is the bottom member 7 of my improved mail box. This bottom consists of a flat piece of sheet metal rigidly connected at a point adjacent one of its longitudinal edges to the standard 5 and provided upon each edge thereof with an up-standing flange 8 and further provided with 60 what will be known as brace flanges 9 which are secured as at 10 to the under face of the bottom 7, said flanges extending from each corner of the bottom member 7 to the standard 5 and integrally connected therewith. 65

The body of my improved mail box which is generally indicated by the numeral 11, is substantially rectangular in form and the end walls thereof are cut upon an angle so that the forward or front side wall of the 70 box is considerably shorter than the rear or back side wall so that when the cover 12 is in its closed position, as illustrated in Fig. 1, the roof of the cover will be in a slanting position so as to prevent any water or dampness from lying thereon. The side and end walls of the body 11 are bent upon themselves at the lower edges thereof to form a channel 13 in which the downwardly extending flanges 14 of the bottom 15 extend, 75 said bottom 15 being preferably the bottom of the mail box 11, while the bottom member 7 is merely a support or rest for the box. The box 11 is secured to the supporting member 1 by means of the bolts 16 which 80 extend through both the bottom members 7 and 15 and are provided upon their lower edges with suitable nuts 17, whereby to securely retain the box 11 in position upon the supporting bottom 7. 85

The front side wall of the box 11 is provided with a movable section 18, the lower edge of which is hinged to the stationary portion of the front wall, as shown at 19 and the ends of this movable section 18 are provided with rearwardly projecting flanges 20 which engage over the forward edges of each of the end walls to prevent any lateral movement on the part of the movable section 18. The cover 12 is provided upon its side and 100 end portions with downwardly projecting flanges which engage over the upper edges of the sides and end walls of the box and the cover is hingedly connected to the body of the box, as shown at 21, so that it may be 105 readily opened and closed. In order to provide means for manually operating the cover,

to open the same, I provide a U-shaped crank shaft 22, the intermediate portion of which is movable within the loops 23 carried by the inner face of the cover 12. The ends 5 of the shaft 22 are bent outwardly at right angles, as shown at 24 and extend through suitable bearings within the end walls of the box. Secured to the ends of the shaft 22 upon the outer side of the box, are the connecting arms 25, said connecting arms having their outer ends bifurcated and adapted to receive the ends of a U-shaped operating member 26', the ends of said operating member being pivotally connected by means of 10 the bolts 26 within the bifurcated ends of the arms 25. The intermediate portion of this operating member extends longitudinally across the front side of the box and is provided with a handle portion 27, whereby 15 the end portions of the same may be readily reciprocated within the guides 28 which are secured to the ends of the box 11. It will be noted that upon the reciprocation of the end portions of the operating member 26', the 20 arms 25 will be actuated to rotate the ends of the shaft 22 within the bearings in the end wall of the box and raise the cover 12 to its open position. It will also be apparent that 25 simultaneous with the opening of the cover, the movable wall 18 will drop outwardly, the same being pressed out by means of the yieldable flange portion 29 formed integral with the upper edge of the rigid portion of the forward wall. From this it will be apparent 30 that when the handle member 27 is grasped, and the end portions of the member 26' reciprocated, the cover 12 and the movable wall portion 18 will be opened simultaneously as the movable wall 18 is normally 35 retained in a closed position by means of the member 30 which is carried by the operating member 26' and normally engages the outer face of the movable wall 18 to retain the same in a closed position, as clearly shown 40 in Fig. 2.

Upon the top of the box I provide an indicator which will notify the owner of the box whether or not the mail-man has deposited any mail within the box and, at the same 45 time, notify the mail-man that there is mail in the box to be collected. This indicator includes a U-shaped rod 31, the ends of which are rotatably mounted within suitable bearings 32 secured to the upper face of the cover 50 12. One end of the rod extends outwardly beyond the bearing and is bent upon itself to form a finger loop 33 which can be readily engaged to rotate the ends of the rod 31 and raise or lower the same. The intermediate portion of the frame formed by the 55 rod 31, is provided with a metal plate 34 which can be painted red or any other desirable color, so that it can be readily seen by both the mail-man and the owner of the box. 60

65 It will be apparent from the foregoing de-

scription, that I have provided a simple and durable mail box, whereby the cover and a portion of the front side thereof can be opened simultaneously by manually operated means. From this it will be noted that 70 by grasping the handle member 27 and reciprocating the end portions of the operating member 26', the cover and movable portion of the front side wall will be opened simultaneously, it being understood that the 75 yieldable flange 29 will engage with the inner face of the movable portion 18 of the front side wall, whereby to open the same simultaneously with the cover, so that persons removing mail from the box will not 80 cut or scratch their hands on the upper edge of the forward portion of the box.

My improved mail box, as herein shown and described, is extremely simple in construction and can be manufactured and 85 placed upon the market at a comparatively low cost.

While I have shown and described the preferred form of my invention, it will be obvious that various changes in the details 90 of construction and in the proportions may be resorted to for successfully carrying my invention into practice, without sacrificing any of the novel features or departing from the scope of the invention, as defined by the 95 appended claims.

Having thus described this invention, what I desire to claim and secure by Letters Patent, is:—

1. A mail box including a body, a movable 100 cover therefor, a shaft carried by the body and having a crank portion loosely connected with the cover, arms secured to the outer ends of said shaft, a U-shaped member having its ends loosely connected with the 105 arms, a hinged portion on one side of the body, means carried by the U-shaped member for normally retaining the hinged portion in closed position, and a yieldable flange carried by the body and normally bearing 110 against said hinged portion, the U-shaped member being adapted to be manually operated whereby to open the cover and release the hinged portion, the yieldable flange forcing the hinged portion outwardly so that 115 both the cover and hinged portion will be opened simultaneously.

2. A mail box including a body, a movable 120 cover therefor, a shaft carried by the body and provided with a crank portion having loose connection with the cover, a U-shaped member carried by the body, means forming connection between the ends of the U-shaped member and the shaft, a handle carried by the U-shaped member, a hinged portion on one side of the body, a yieldable flange normally bearing outwardly upon said hinged portion, and a handle member carried by the U-shaped member whereby the same may be reciprocated to open the cover and release 130

the hinged portion so that the latter may move to its open position.

3. A mail box including a body having a movable top and side wall, said side wall being supported in its closed position by the top when the latter is closed, and manually operable means for moving the top to open position and releasing said side wall, said means including a rectilinearly movable element adapted to constitute a support for the movable side wall and limit its movement to open position.

4. A mail box including a standard, a hollow standard adjustable with respect to the first standard, a bottom member carried by the second standard, and having upturned flanges, a body having its side and end walls bent upon themselves at their lower edges to form channels, a second bottom having down-turned flanges adapted for engagement within the channels formed by the up-turned flanges, a movable cover for the body, and means for simultaneously opening and closing the cover on one side of the body.

5. A mail box including a body having a movable top and side wall, manually operable means for moving the top to its open

position including a rectilinearly movable element which acts to sustain the side wall in its closed position when the top is closed, 30 and means urging the movable side wall to its open position when said element is operated to move the top to open position.

6. A mail box including a body having a movable top and side wall, said side wall being held against outward movement by the top when the latter is closed, manually operable means for moving the top to open position including a member arranged within the box and slidably connected to the under 40 side of said top, and a rectilinearly movable element extending longitudinally of the side wall exteriorly thereof, and means acting to urge the movable side wall to open position when said element is operated to open the 45 top of the box, said element constituting a support for said side wall and limiting its movement to open position.

In testimony whereof I hereunto affix my signature in the presence of two witnesses. 50
